UNITED STATES PATENT OFFICE.

HJALMAR OLIVIER DAHL, OF STOCKHOLM, SWEDEN.

DRAFT-TUBE FOR TURBINES.

1,882,612.

Specification of Letters Patent.

Patented Mar. 2, 1920.

Application filed August 9, 1917. Serial No. 185,373.

To all whom it may concern:

Be it known that I, HJALMAR OLIVIER DAHL, a subject of the King of Sweden, and resident of Upplandsgatan No. 60, Stockholm, in the Kingdom of Sweden, have invented certain new and useful Improvements in Draft-Tubes for Turbines, of which the following is a specification, reference being had therein to the accompanying drawing.

The present invention refers to an arrangement in draft tubes for reaction and full admission turbines, and is essentially characterized by the fact that there is arranged, immediately at the outlet of the turbine a body or core having a smooth surface and the diameter of which increases in the outlet direction, and that the part of the suction pipe, as it leaves the turbine, is gradually enlarged; as a result of these arrangements, the water, after having passed the runner, will pass annular surfaces of increasing mean diameter, and constant or increasing cross section area in order to effect a higher utilization of the component of rotation of the velocity of the water than is otherwise possible, and to enable a changing of the energy of motion of the water into energy of pressure for a very short distance, whereby the losses in the continuation of the draft tube are reduced, especially when the water-passage is immediately curved, as in suction bends and twin draft tubes.

The invention is further characterized by other arrangements, which will be herein-after set forth, in connection with some suitable embodiments.

Referring to the accompanying drawings, Figure 1 illustrates, in section, a form of the invention in which the core is free of the casing, Fig. 2 illustrates a form in which the core extends inwardly from the casing, Fig. 3 illustrates a form of my invention as embodied in a double turbine apparatus.

In Fig. 1, 1 is the water guide of the turbine, provided with the guide blades 1*. 2 is the runner of the turbine, fixed to the shaft 2* which is journaled in suitable bearings, not shown. 3 is the draft tube, connected with the said water guide.

According to the present invention, a central body or core 4 is located in the draft tube 3 immediately at the outlet of the turbine. As shown in the said figure, the core has a

smooth surface of revolution and the diameter of same increases gradually in the outlet direction. The part of the draft tube 3 surrounding the central body 4 and situated nearest to the turbine is gradually enlarged.

The said shape of the top part of the central body and the part of the draft tube surrounding the same forms the essential feature of the invention. The lower part of the body may be shaped as shown, for instance its diameter may gradually decrease or it may be shaped otherwise. The same is the case as to the lower part of the draft tube, which in Fig. 1 is cylindrical.

Preferably, the central body or core is stationary, in which case, the said body or core 4 is fixed to the draft tube 3 by means of ribs 4*.

The draft tube with the core acts in the following manner: The water enters the draft tube as indicated by the arrows. As the water leaves the runner, it generally has a component of rotation, which decreases as the distance of the water particle from the axis of the turbine increases. Consequently, the absolute pressure of the water increases while the water passes the top part of the draft tube and the desired changing of the energy of motion of the water into energy of pressure is effected. At the same time, the axial component of velocity of the water is changed into energy of pressure for a shorter distance than is the case without the central core.

When the water-passage is to be curved, the draft tube and the central body may be shaped as shown in Fig. 2. In that illustration, the central body consists of a bulge formed in the wall of the draft tube 3. This arrangement may evidently, be applied to single turbines as well as to double ones, with horizontal shaft or vertical shaft and suitably modified, and also in such cases, in which the angle between the turbine shaft and the outlet direction of water possibly differs from 90°. Owing to the fact that the velocity of the water is rapidly reduced for reasons stated above, the draft tube may be immediately curved without great losses of energy.

In Fig. 3 is shown a draft tube 3 with two central bodies 4, 4 and adapted for a double turbine with a common outlet 5 for the water. The central bodies 4, 4 are connected with one another at their bases as

shown. This construction permits the draft tube bend or suction conduit to be materially shortened and broadened.

What I claim is:—

- 5 1. In combination, a draft tube for a turbine and a single body within and surrounded by said tube, the said body having a curved sectional profile and an unobstructive outer surface, the diameter of said body gradually increasing in the outlet direction, and the inner part of the tube surrounding said body being gradually enlarged in the said direction.
  - 10 2. In combination, a draft tube for a turbine, a turbine runner, and a single body within and surrounded by said tube and leading directly from the runner, the said body having a curved sectional profile and an unobstructing outer surface, the diameter of said body gradually increasing in the outlet direction, and the inner part of the tube surrounding said body being gradually enlarged in the said direction.
  - 15 3. In combination, a draft tube for a turbine; a rotatable turbine runner; and a single non-rotatable body within and surrounded by the tube, the surface of the runner leading directly into that of the body,
- said last-named surface being unobstructing and said body having a curved sectional profile and of a diameter which gradually increases in the outlet direction, and the inner part of the tube surrounding said body being gradually enlarged in the same direction. 30
- 35 4. A draft tube for a turbine and a single body projecting into the tube from a wall thereof and surrounded by part of the tube, the said body having an outer surface, the diameter of which gradually increases 40 in the outlet direction, and the inner part of the part of the tube surrounding said body being gradually enlarged in the said direction.
  - 45 5. A draft tube for a turbine and a single body within the tube and connected with a wall thereof and surrounded by part of the tube, the said body having an outer surface, the diameter of which gradually increases in the outlet direction, and the inner part of the part of the tube surrounding said body being gradually enlarged in the said direction. 50

In witness whereof, I have hereunto signed my name.

HJALMAR OLIVIER DAHL.
